WALK-IN COOLER

Paavo V. Suominen, 5 Tikantie, Tampere 10,
Finland 33100

Filed Aug. 16, 1974, Ser. No. 498,076

Claims priority, application Finland Feb. 20, 1974

Term of patent 14 years

Int. Cl. D15—07

U.S. Cl. D67—3 R

FIG. 1

FIG. 2

FIG. 3

FIG. 1 is a perspective view of a walk-in cooler embodying my new design;

FIG. 2 is a rear perspective view thereof; and

FIG. 3 is a top plan view thereof.

The bottom is plain and not ornamented; the side opposite to that shown in FIG. 2 is identical.

I claim:

The design of a walk-in cooler, as shown and described.
